STEPLADDER GUARD ATTACHMENT

Filed Dec. 23, 1943

UNITED STATES PATENT OFFICE

2,423,477

STEPLADDER GUARD ATTACHMENT

Gaston Brimboeuf, New York, N. Y.

Application December 23, 1943, Serial No. 515,351

3 Claims. (Cl. 228—24)

1

This invention relates to stepladders and more particularly to a stepladder guard attachment and is an improvement on my prior Patent No. 2,208,833, issued July 23, 1940, for Stepladder guard attachment.

An object of this invention is to provide a stepladder guard attachment which may be mounted on any stepladder, new or old, and extending upwardly from a stepladder to provide a support which may be held by a person on the stepladder, or against which a person on a stepladder may lean, while using the stepladder, also enabling the person to stand, even at the top end of the stepladder thereby instilling confidence and a sense of security, thus avoiding the hazard of accidents or falling off, and giving free movement of both hands while performing any kind of work ordinarily performed on stepladders; said attachments being further adapted to support a pail or basket or tools, or combination detachable shelf and tool box for use by painters, fruit pickers, electricians, housewives, etc.

Another object of this invention relates to the provision of said stepladder guard serving as a ladder extension and which is hinged to the top of the stepladder in such a manner as to lie against the same when not in use, and which when moved into operative position will provide a double platform at the top of the stepladder.

A further object of this invention relates to the provision of a rigid supporting brace arranged one on each side of the stepladder extending downwardly and outwardly from the top thereof, which braces may or may not be adjustable as to length, and which are further provided at their lowermost ends with ground engaging members whereby to prevent sidewise slipping or tilting of the stepladder as well as to prevent sinking of the stepladder when the same is placed on soft ground, or tipping of the stepladder when placed on a surface that is not level.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Figure 1 is a perspective view of the stepladder 55

2

showing the stepladder guard and side supporting braces operatively attached thereto.

Figure 2 is a perspective view of the stepladder and its attachments collapsed or in folded position.

Figure 3 is a detail view of one form of the supporting side braces.

Figure 4 is a detail sectional view taken on line 4—4, Figure 1.

Figure 5 is a detail view of one end of one of the stepladder guard's locking braces.

Figure 6 is a detail view of another form of supporting side brace.

Referring to the drawing in detail, 10 denotes 15 a conventional form of collapsible stepladder comprising a ladder portion 11 provided at its upper end with a platform 12. Hinged to a part of the platform 12 as at 13 is a pair of supporting legs 14, at least one of said legs being connected 20 to the ladder 10 by a folding linkage 15 in the manner well-known. The part of the platform 12 mounting the hinge pins 13 consist of side bars 16 which are rigidly secured to the platform and the upper ends of the ladder 11.

25 The ladder guard and extension indicated generally by the reference character 20 comprises a platform 21 hinged in any suitable manner as at 22 to the rear edge of the stepladder platform 12, and an upright ladder 23 formed of legs 24 and 30 rungs 25. Fixed to the underside of the ladder guard platform 21 are a pair of triangular bracket elements 26 arranged respectively in the same plane as the legs 14 and each having an edge 27 arranged to abut an outer edge 28 of said legs 35 when the platform 21 is moved to horizontal operative position as clearly shown in Figure 1, said bracket elements 26 serving to brace the ladder guard platform 21 and to hold the same in its horizontal position which is co-planar with the 40 stepladder platform 12. The ladder 23 is rigidly secured to the ladder guard platform 21 adjacent the edge thereof remote from its hinge edge, and the width thereof as well as that of the ladder guard platform corresponds, respectively, with 45 that of the ladder 11 and platform 12.

To brace the ladder guard 23 there is provided a pair of locking brace rods 30, each pivotally connected at its lower end as at 31 to the step ladder side bar 16, one at each side of the step-ladder. Formed on the other end of each of the brace rods 30 is a bayonet slot 32 arranged to co-act with a threaded pin 33, there being one such pin on each of the ladder legs 24 adjacent the upper end thereof. Fitted on each of the pins 33 is a wing-nut 34.

In the collapsed position of the ladder guard 23, the platform 21 thereof rests on and overlaps the stepladder platform 12, such that the ladder 23 depends downwardly in front of the ladder portion 11, as shown in Figure 2, and with the brace rods 30 extending downwardly alongside of the legs of the ladder portion 11.

When it is desired to place the ladder guard 20 in operative position, the same is swung upwardly until the bracket elements 26 engage the supporting legs 14. The brace rods 30 are moved up and the bayonet slots 32 hooked into position on the pins 33 and locked in place thereon by setting up on the wing-nuts 34. In this manner the ladder guard 20 is securely locked and braced to the stepladder 10, which latter of course must be opened for use as shown in Figure 1. It will be observed that the ladder guard 20 thus provides a double platform 12-21 at the top of the step-ladder providing a more roomy and substantial foot support for a person standing thereon, the ladder 23 serving as a guard, support and a ladder all as described in the above statement of the invention. The above described ladder guard is easy to assemble and adjust, requiring only a detachment and attachment of the brace rods 30 to move the same into inoperative and operative position. To prevent tilting or sidewise tipping of the combined stepladder and ladder guard as well as to brace the same there is provided on each side thereof a lateral brace 40. Each lateral brace comprises a rod 41 having its upper end portion bent angularly as at 42 for insertion into a suitable opening 43 formed in the side bar 16, there being provided on the end of said angular connecting end 42, a head 44 for retaining said rod 41 secured against accidental displacement. The lower end of the rod 41 is telescoped in a sleeve 45 provided with a set screw 46 for securing the same in adjusted position therein. Pivottally connected to the lower end of the sleeve 45 through the medium of the pins 47 is a ground engaging plate or shoe 48.

In some instances the adjustable feature of the lateral brace 40 may be dispensed with and the rod 41a, see Figure 6, may be provided at its lower end with a rubber boot 50 adapted to engage the ground.

Both forms of lateral braces will function to prevent sidewise tilting or tipping of the combined stepladder and guard as well as slipping thereof. Where the stepladder is used on soft ground, the adjustable lateral brace 40 with ground engaging plate 48 will prevent the stepladder from sinking into the ground. Both forms of braces are further useful in supporting the stepladder when the same rests on an uneven surface, as a pavement, for example. The lateral braces may be used with or without the ladder guard attachment.

Having thus described the invention, what is claimed is:

1. In a stepladder of the collapsible type comprising a ladder portion having a platform at its upper end and a pair of side bars below said platform, a supporting leg portion hinged at its upper end to said side bars and a folding linkage

interconnecting said ladder and leg portions; a ladder guard hingedly connected to said stepladder platform and adapted to be swung downwardly against said ladder portion when in inoperative position, a pair of locking brace rods pivoted at their lower ends to the forward ends of said side bars, and quick attachable means on the other ends of said brace rods for coaction with cooperating holding means on said ladder guard for holding the latter locked in its operative upright position, said ladder guard comprising a guard platform, hinge means connecting said guard platform to the rear edge of said stepladder platform, a ladder secured to said guard platform and normal thereto, bracket elements fixed to the underside of said guard platform and adapted to abut said supporting leg portion to brace and support said ladder guard, a pair of lateral brace elements arranged one on each side of said stepladder and each connected to a side bar, and a ground engaging member on the lower end of each brace element.

2. In combination, a ladder having a series of steps and a platform above the steps, an extension hinged to the side of the platform to provide in open position a horizontal extension thereof, side bars connected with said extension and provided with a series of steps rising above said extension, said extension being adapted to fold against the platform and said side bars and steps being adapted to fold against the ladder and to align the steps of said side bars with the steps of the ladder, and braces connected to the platform of the ladder and to the sides of the side bars to support said side bars and the steps thereof in an elevated position over the ladder.

3. In combination, a ladder including uprights and steps connecting the uprights to each other and a platform at the top of the uprights, side legs pivotally connected to the upper end of the uprights, a folding brace for supporting the side legs in angular relation to the ladder, an extension hinged to one side of the platform and provided with brace members adapted to rest against the side legs in open position to support said extension in approximately the same plane as the platform, side bars carried by the extension, steps carried by the side bars and having a spacing corresponding to that of the spacing of the ladder steps, brace members pivotally connected with the sides of the upper end of the ladder, and means for detachably connecting the brace members with the side bars to support said side bars in elevated position over the ladder and the side legs.

GASTON BRIMBOEUF.
